ARC CHUTE

William M. Scott, Jr., Bryn Mawr, Pa., assignor to
 I-T-E Circuit Breaker Company, Philadelphia,
 Pa., a corporation of Pennsylvania

Application January 12, 1945, Serial No. 572,553

4 Claims. (Cl. 200—147)

1

My present invention relates to circuit interrupters and more particularly to a novel arc quencher therefor comprising a plurality of spaced plates of insulating material arranged above and parallel to the arc, the said plates being intersected by a number of transverse metallic rods.

More specifically, my invention relates to a novel and simplified blow-out means readily adapted to be used in connection with the said metallic rods and which requires a minimum of additional parts and virtually no maintenance and repair.

This application embodies some of the principles of my application Serial No. 550,179, filed August 19, 1944, and embodies substantially the disclosure therein set forth together with the additional simple and novel blow-out mechanism.

Essentially, my invention contemplates that the upper transverse metallic rods have an iron core in order to provide a magnetic blow-out. These upper transverse rods may also extend through a pair of ferrous side plates in order to enhance the blow-out effect.

In the construction and operation of circuit interrupters, it is frequently necessary to provide means for extinguishing quickly the arc which is drawn between the contacts as they separate. Such circuit interrupters, which may be tripped open on the incidence of high currents, comprise a pair of main contacts (to carry the full current during normal operation), which are arranged to make after and break before a pair of parallel arcing contacts so that any arcing which may occur will not pit or otherwise destroy the contact surfaces of the main contacts.

The arc which is drawn between the arcing contacts when they separate under over-current conditions is blown upwardly by blow-out means, such as a magnetic blow-out or air blast (both well known in the art) into an arc chute which is arranged to quench the arc by lengthening the same or cooling it, by a combination of these methods or in many other ways.

Arc chutes having spaced insulating plates to lengthen the arc or squeeze the arc into narrow slots are well known.

My invention contemplates as its essential function the provision of an arc chute which utilizes both the principle of spaced insulating plates to lengthen and squeeze the arc, together with a series of metallic surfaces with which the arc is brought into contact and broken up into a series of small arcs and cooled.

More specifically, my invention contemplates a plurality of spaced insulating plates extending

2

in a direction parallel to the path of the arc into which the arc is forced by blow-out means, the said spaced insulating plates being used in combination with a series of transverse metallic members which will break the arc into a plurality of arcs in series and will also further cool the same.

Still more specifically, my invention contemplates that these metallic surfaces be formed by a series of transverse pins, each of which extends through all of the insulating plates and each of which furnishes a conductive path between the various slots defined by the spaced insulating plates.

The primary object of the present invention is 15 the provision of simplified blow-out means which comprises making a substantial portion of the transverse metallic rods or pins of the arc chute of a suitable conductive material, such as copper, but making the upper row or rows of transverse 20 pins of iron in order to provide a suitable magnetic blow-out. These upper iron transverse pins may have a sleeve or coating of copper in order that these upper pins may also act as arc extinguishing pins.

25 Another object of my invention is the arrangement of the upper iron copper coated transverse rods or pins so that they may cooperate with or form a part of other blow-out means such as a pair of ferrous side plates.

30 These and many other objects of my invention will become apparent in the following description and drawings in which:

Figure 1 is an end view taken from line 1—1 of Figure 2 of my novel arc extinguisher.

35 Figure 2 is a view partly in cross section taken from line 2—2 of Figure 1 looking in the direction of the arrows and showing the compound upper two rows of transverse pins which have an iron core and copper coating or sleeve.

40 Figure 3 is a front view of a slightly modified form of arc extinguisher in which the construction of the upper two rows of compound pins is slightly varied so that these pins may cooperate with a pair of ferrous side plates.

45 Figure 4 is a side view of the arc chute of Figure 3 showing one of the ferrous side plates.

Figure 5 is a longitudinal cross sectional view taken on line 5—5 of Figure 3 showing the construction of the compound copper-iron blow-out pin.

Figure 6 is a cross sectional view taken on line 6—6 of Figure 5 further showing the construction of the compound copper-iron pin of the arc chutes of Figures 3 and 4.

55 Referring now to Figures 1 and 2, I have here

shown an arc chute corresponding in every respect to the arc chute disclosed in my application Serial No. 550,179, except that the magnetic blow-out coil in series with the arcing horn is no longer used, but instead the upper two rows of pins in the embodiment shown have iron cores and copper coatings or sleeves.

The arc quencher 20 also has the construction and operation generally shown in my Patent No. 2,348,228. The arc chute 20 comprises a pair of side supporting plates 21, 21 of insulating material, between which are mounted a number of spaced arc extinguishing plates 23, 24, 25, 26, 27, also of insulating material. The plates are integrated as a single unit by the transverse bolts 30, 31, 32, 33, which are provided with insulated bushings 35, 35.

Bolts 30 and 31 are also provided with individual insulating washers or spacers 37, 37 to maintain the spacing between the insulating plates at the front of the arc quencher. Bolts 32 and 33 carry a set of insulating spacers 38 between each pair of plates which serve to space the back ends of the plates from each other; the said spacers 38 also each having a hook-shaped extension 39 to engage a hook 40 on the upper end of the arcing horn 41, which is secured to the back panel 42 on which the circuit breaker is mounted. The plates 23-27 are accordingly insulated from each other and from the side plates 21.

The side plates 21, 21 also carry between them on the transverse bolts 44 and 45 the opposite arcing horn 46. The said arcing horn 46 has an extension 47 carrying a bolt 48 which may be secured to the stationary flange member 49 carried by the transverse insulating bridging support 50 in order to secure the arc chute in position. A conductive connection is made to the arcing horn 46 through the flange member 49 and the pigtail 52.

The arc quencher 20 is particularly characterized by a large number of transverse copper pins 60, 60 which pass through perforations in the plates 23, 24, 25, 26, 27, as shown in Figures 1 and 2, and which are supported thereby. The pins 60 preferably do not contact the opposite supporting insulating members 21, 21. This will facilitate assembly and adjustment of the unit, permits the pins to be brought down close to the contacts which form the arc, removes the possibility of breakdown or creepage along the supporting plates 21, 21. The remainder of the structure shown corresponds to the circuit breaker shown in my Patent No. 2,348,228.

Essentially, the circuit breaker here shown comprises a lower back connection stud (not shown) to which the main movable contact 72 (on the contact arm 65), the arcing horn 46-47, and the arcing contact 78 are connected respectively by a pigtail (not shown), pigtail 52, and pigtail 66. The circuit breaker also comprises an upper back connection stud 70 to which is secured the main stationary contact 71, which engages the main movable contact 72 mounted on the contact arm 65 to complete a circuit from the upper to the lower connection studs. And also mounted on the back connection stud 70 is the connecting bracket 73 which is connected to the stationary arcing horn 41 at the end of which the stationary arcing contact 77 is carried.

When the main contacts 71 and 72 have separated, while the arcing contacts hereinafter described are engaged, current flows from the back connection stud 70 through the connecting

bracket 73 and the lower end of the arcing horn 41, to the stationary arcing contact 77, then to the movable arcing contact 78 mounted on the contact arm 65, and then through the pigtail 66 to the lower back connection stud.

As arcing contacts 77 and 78 separate, an arc is drawn therebetween. As the opening movement is completed, the root of the arc at contact 77 is blown upwardly along the arcing horn 41 while the root of the arc at movable arcing contact 78 is transferred to arcing horn 46 and blown upwardly thereon. The blow-out means, hereinafter more specifically described, blows the center of the arc upwardly into the center of the plates 23 to 27. The plates 23 to 27 are longest in a vertical direction at plates 23 and 27; that is, the downwardly extending cusps 80 thereof extend further downwardly in the case of these plates. The center plate 25 has the shortest cusp 82. The intermediate plates 24 and 26 have cusps 81 of intermediate length, as shown more particularly in Figure 2 and in dotted lines in Figure 1.

Thus, in a transverse direction, the plates of the arc chute present a V-shape which tends to guide the arc toward the center of the chute. The downwardly extending cusps 80, 81 and 82 intercept the center of the arc and tend to guide the arc in its upward movement to squeeze into the confined space between the plates.

The arc in being driven upwardly tends to be squeezed into but one of the spaces, for instance, in the space 85 between plates 24 and 25 or in the space 86 between plates 25 and 26. It is not necessarily confined to either or both of these spaces but may be broken up into a plurality of parallel arcs in separate spaces.

While this type of arc chute having only the spaced insulating plates 23 to 27 has been effective in use, it has been found that perhaps only one or two of the spaces, and usually only one, are actually effective in extinguishing the arc. That is, the arc is forced up into but one of the four spaces which it may normally enter, is squeezed between the surfaces of the plates defining the space, and is extinguished therein.

The arc, in addition to being initially compressed in one or two of the slots or spaces between the plates, is intercepted transversely by the plurality of metallic surfaces which define the pins 60. These pins 60, which are of highly conductive material, preferably copper, tend to break the arc up in series among them. That is, should the arc be squeezed, say, into the slot 85, it will encounter a number of pins 60, as shown by the dotted line 90, and will be broken up into a series of small arcs between these pins.

In addition, as the arc is driven upwardly, the initial small series arcs will go out and new arcs, as indicated at 91, will be established across other pins, which effect a new cooling action on the arc. As the arc moves still further upwardly, it will encounter still more pins and be broken up into a larger number of small arcs in series. This continuous tearing of the roots of the small arcs from the lower pins and reestablishing the small arcs above the small arcs which have been extinguished, will render the arcs unstable and lead to quick extinguishment.

The surfaces of the pins 60 will tend further to cool the arc while the arc roots move along from pin to pin, and will result in quick extinguishment of the arc. Not only does this action take place within the principal slot (for instance, 85) into which the arc is first squeezed, but by

reason of the fact that the pins extend through all of the slots, arcs may be set up in adjacent slots. Thus, for instance, when a small series arc is drawn between any two of the pins, the current in that arc may flow transversely through the chute (longitudinally through the pins) into adjacent slots. The pins are sufficiently close for the particular voltage for which the circuit breaker is rated so that at the substantial interrupting currents involved, new arcs may flash over between the adjacent pins in other slots when the arc roots are torn away from the pins in the original slot, thus transferring a portion of the arc to another and cooler slot and rendering the arc as a whole even more unstable.

By this structure, therefore, the arc is first squeezed into one or more slots which extend parallel to the arc path and into which the arc as a whole is squeezed between insulating plates. When squeezed into the slots between these insulating plates, the arc encounters a large number of spaced transverse pins. These pins break the arc up into a series of small arcs between them and by reason of the rapid movement of the arc with respect to the surfaces of these pins and upwardly from pin to pin, tend to cool the roots of the small series arcs. This tends quickly to extinguish the arc.

Furthermore, since each pin extends through all of the slots, there is a tendency for the current to flow along the pins and for a small arc to strike over between closely adjacent pins of another slot when the arc roots are torn from the same pins in the original slot, thus forming some of the series arcs in a cooler slot, again rendering the arcs highly unstable and tending quickly to extinguish them.

This combination of squeezing the arc between insulating plates, intercepting the arc by metallic members or pins, breaking the arc up into a plurality of small arcs in series with each other and causing some of the small arcs to strike over in adjacent slots, results in a very quick extinguishing action.

I have found that, in addition to their primary function of breaking the arc into a series of small arcs, the metallic pins 60 provide a conductive path between the spaces between the various plates, and aids materially in the extinguishing of the arc.

Interphase barriers 89 may be provided between adjacent poles which usually have individual arc chutes. Such interphase barriers will prevent any flash over of the arc from one pole to the other. The arc chute is supported at the front of the circuit breaker by the front lower edges of plates 21 which rest in the slots 97, 97 of the supporting bridge 50. The back of the arc chute is supported by the hook 39 which engages the hook 40 of the arcing horn 41.

The arc chute 20 is locked in place by the bolt 43 which engages the flange 49. The arc chute may be readily removed for inspection and repair, or for replacement of other elements of the circuit breaker simply by rotating bolt 43 so that it will disengage flange 49. Upon such disengagement, the arc chute may simply be pulled forward and removed. The pins 60 and plates 23 to 27 are preferably assembled together first as a unit and then assembled with the arc chute by placing the plate and pin assembly between the plates 21 and passing the bolts 36 to 38 through aligned openings in the plates.

As will be obvious from Figure 1, the insulated supporting plates 21, 21 carry on their outer sur-

faces iron plates 95. In the embodiment shown, the upper two rows of pins, instead of being of solid copper, as are the pins 60, have iron cores 100 with a copper coating or sleeve 101 thereon. 5 The copper coating or sleeve ensures that these upper rows of pins will also have the appropriate cooling and conductive effect equivalent to that of the lower pins 60; while the iron centers 100 of the upper two rows of pins provide a path 10 for a U-shaped magnetic blow-out circuit which includes the ferrous plates 95 as well as the iron cores 100 of the upper rows of pins. Thus, no additional blow-out means is necessary. The arc loop within the arc chute provides a sufficient 15 half-turned current loop to create an appropriate magnetic field between the opposite plates 95; while the iron cores 100 of the upper rows of pins serve to reinforce and complete the magnetic circuit to create a blow-out. By this means, 20 therefore, the necessity for special blow-out magnets is obviated.

In Figures 1 and 2, I have shown the upper rows of pins 100 with their copper coatings or sleeves 101 extending through the arc chute in 25 the same manner as the pins 60, that is, they do not come into contact with the insulating side walls 21, 21 of the arc chute nor do they contact the ferrous plates 95.

As seen in Figures 5 and 6, the iron core pins 30 200 have an insulating coating or sleeve 202 around which is formed a copper coating or sleeve 201. The copper coating or sleeve 201 serves the same function as the coating or sleeve 101 of Figures 1 and 2. The copper coating or sleeve 201 has preferably the same length as the pins 60 and extends to within a very short distance on either side of the inner surfaces of the insulating side walls 21 of the arc chute housing.

The insulating sleeve 202 around the iron pins 40 200 extends at 203, 203 for a sufficient distance on either side of the copper coating or sleeve 201 so that the iron pins will be insulated from the arc between the end of the copper sleeve or coating 201 and the insulated side walls 21 of the 45 housing. For additional safety, the portions 203, 203 of the insulating sleeve 202 are sufficiently long to pass entirely through the openings 205 and to the outer surfaces of the insulating side walls 21 of the housing.

50 The end surfaces 206, 206 of the iron core 200 bear against the inner surfaces of the ferrous plates 95. In appropriate cases, the inner surfaces of the ferrous plates 95 may be provided with recesses or even through perforations or 55 holes to receive the ends 206 of the iron pins 200. By this means, the iron core pins establish a complete low reluctance U-shaped magnetic path in order to generate a magnetic blow-out of great strength which will move the arc very rapidly, the arc of course forming a half turned 60 current loop for energizing the magnet 95, 200, 95.

65 By the means herein described, a portion of the means which are used to extinguish the arc may also readily be used as the blow-out means. The blow-out mechanism thus formed is entirely magnetic, it is very simple, requires no replacement or repair, and yet does not in any way diminish but, in fact, increases the cooling and extinguishing powers of the arc chute.

In the foregoing, I have described my invention solely in connection with specific preferred embodiments thereof. Since many variations and modifications of my invention should now be apparent to those skilled in the art, I prefer to

be bound not by the specific disclosures herein but only by the appended claims.

I claim:

1. An arc chute comprising means for drawing an arc; means for moving the arc into the chute; and arc extinguishing means within the arc chute; said means for moving the arc into the chute comprising a plurality of ferrous pins extending transverse to the arc path substantially remote from the point of entry of the arc into the arc chute; a pair of ferrous plates on either side of the arc chute coacting with said transverse ferrous pins to form a U-shaped magnetic path; a plurality of insulating plates extending in planes parallel to the path of the arc, said insulating plates supporting said transverse ferrous pins in spaced relation to each other.

2. An arc chute comprising means for drawing an arc; means for moving the arc into the chute; and arc extinguishing means within the arc chute; said means for moving the arc into the chute comprising a plurality of ferrous pins extending transverse to the arc path substantially remote from the point of entry of the arc into the arc chute; a pair of ferrous plates on either side of the arc chute coacting with said transverse ferrous pins to form a U-shaped magnetic path; said arc chute having a pair of insulating side walls arranged parallel to the path of the arc; said transverse ferrous pins extending through and being supported by said insulating side walls; said ferrous plates being supported by said insulating side walls; the ends of said transverse ferrous pins engaging said ferrous plates.

3. An arc chute comprising means for drawing an arc; means for moving the arc into the chute; and arc extinguishing means within the arc chute; said means for moving the arc into the chute comprising a plurality of ferrous pins extending transverse to the arc path substantially remote from the point of entry of the arc into the arc chute; a pair of ferrous plates on either side of the arc chute coacting with said transverse ferrous pins to form a U-shaped magnetic path; said arc chute having a pair of insu-

5

lating side walls arranged parallel to the path of the arc; said transverse ferrous pins extending through and being supported by said insulating side walls; said ferrous plates being supported by said insulating side walls; the ends of said transverse ferrous pins engaging said ferrous plates; said ferrous pins having an insulating sleeve extending along the length thereof at least up to the interior surfaces of said insulating side walls.

4. An arc chute comprising means for drawing an arc; means for moving the arc into the chute; and arc extinguishing means within the arc chute; said means for moving the arc into the chute comprising a plurality of ferrous pins extending transverse to the arc path substantially remote from the point of entry of the arc into the arc chute; a pair of ferrous plates on either side of the arc chute coacting with said transverse ferrous pins to form a U-shaped magnetic path; said arc chute having a pair of insulating side walls arranged parallel to the path of the arc; said transverse ferrous pins extending through and being supported by said insulating side walls; said ferrous plates being supported by said insulating side walls; the ends of said transverse ferrous pins engaging said ferrous plates; said ferrous pins having an insulating sleeve extending along the length thereof at least up to the interior surfaces of said insulating side walls; and a conductive metallic coating over said insulating sleeve.
